CLAIM

The ornamental design for a tablet computer, as shown and described.

DESCRIPTION

FIG. 1 is a front, right and bottom perspective view of a tablet computer, showing my design.

FIG. 2 is a rear, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view thereof, taken from encircled portion 9 in FIG. 1; and,

FIG. 10 is an enlarged view thereof, taken from encircled portion 10 in FIG. 2.

The broken lines shown in the drawings are included for the purpose of illustrating portions of the tablet computer that form no part of the claimed design. In addition, the dot-dash broken lines in FIGS. 1-2 and 9-10 depict the boundaries of the enlargements that form no part of the claimed design. The dash-dot-dash broken lines in FIGS. 1, 2, 9 and 10 are included to show an enlarged view only and form no part of the claimed design.
